FIG. 1

FIG. 2

FIG. 3

FIG. 4

FIG. 1 is an isometric view taken from above and looking towards the front and one side of a hand operable blaster showing my new design;

FIG. 2 is a front elevational view of the hand operable blaster shown in FIG. 1;

FIG. 3 is a bottom view of the hand operable blaster shown in FIGS. 1 and 2; and

FIG. 4 is a top plan view of the hand operable blaster shown in FIGS. 1, 2, and 3.

The side opposite the clip in FIG. 1 is similar thereto except for the absence of the clip, and the left end is arcuate as seen in FIGS. 3 and 4. All sides are unornamented.

I claim:

The ornamental design for a hand operable blaster, substantially as shown and described.
